(57) **CLAIM**

The ornamental design for a counterweight for a construction machine as shown and described.

DESCRIPTION

FIG. 1 is a first perspective view of a counterweight for a construction machine showing our new design;

FIG. 2 is a second perspective view thereof;

FIG. 3 is a front view thereof; and,

FIG. 4 is a left side view thereof, the opposite side being a mirror image of the side shown herein.

The broken lines depict portions of the counterweight for a construction machine in which the design is embodied that are not considered part of the claimed design.
